SEMICOMPOND MULTIPLE EXPANSION
STEAM ENGINE

Russell R. Waterman, Lodi, Calif.

Application July 24, 1944, Serial No. 546,344

3 Claims. (Cl. 121—103)

1

This invention relates to steam engines, the main object being to provide a steam engine having high and low pressure cylinders, and provided with porting and a control valve arrangement so designed that the engine may be run compound or high pressure steam fed to the low pressure cylinder so that the engine will run simple.

By reason of this arrangement extra starting torque and hence added power may be obtained when desired, as when starting a load, without making the engine unduly large, and retaining the economical advantages of a compound engine when the need for this extra power is not present.

Another object is to arrange the porting and control valve so that the change in operation of the engine from compound to simple, and vice versa, is effected by merely changing the length of the stroke of the valve—an operation which may be performed by utilizing any of the conventional types of valve gearing or linkage such as are used to change the valve cut-off in conventional engines.

The low pressure cylinder is of the uniflow type, while the high pressure cylinder is of the counter-flow type; and another object is to arrange the inter-communicating porting, and the control valve, so that the high pressure cylinder becomes the steam measuring cylinder for the low pressure cylinder; thus eliminating the troubles now had with valve actions of such engines when operating on the extremely short cut-offs desirable to obtain proper efficiency therewith.

In other words, the use of a uniflow low pressure cylinder automatically eliminates unbalanced pressures between operating cylinders.

A further object of the invention is to provide a simple and inexpensive device, and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a diagram of my improved engine showing the pistons at the opposite ends of their stroke, and with the control valve set for simple engine operation.

Figure 2 is a similar view showing the pistons and valve at half-stroke position.

Figure 3 is a similar view showing the valve set for compound engine operation.

2

Figure 4 is an end diagram of the engine with the crank at half-stroke and illustrating the use of a conventional type of valve linkage for controlling the setting of the valve.

Referring now more particularly to the characters of reference on the drawings, the engine comprises a high pressure cylinder 1 and a low pressure cylinder 2, the cylinders having pistons 3 and 4, respectively, connected by piston and connecting rod units 5, as usual, to cranks 6 set 180° apart, so that the pistons travel in opposite directions and are at opposite ends of the respective cylinders when the cranks are in dead-center position.

15 A valve chest 7 is mounted in connection with the cylinders, having a steam intake pipe 8 connected thereto at one end. A hollow open-ended piston valve 9 is slidable in the chest, said valve having a rod 10 projecting from one end thereof and which is connected to the control valve linkage 11 of any suitable type mounted on the crankshaft, and by means of which the length of the valve stroke or its cut-off may be altered, so that the valve will move selected different distances to either side of a central transverse line 12 in the chest.

20 The valve 9 as a whole is of reduced size relative to the diameter of the chest and includes end pistons 13 fitting the chest and central pistons 14 also fitting the chest and spaced apart sufficiently to leave an annular channel 15 therebetween which communicates with the interior of the valve through ports 16.

25 Steam passages 17 communicate with the high pressure cylinder 1 at its ends and with the chest 7 at such points equal distances from the line 12 as to be closed by the pistons 13 when the valve is in central position, as shown in Fig. 2. One passage 17, however, is open to the chest between adjacent pistons 13 and 14 when the valve is at the corresponding end of its stroke (whether set for a long or short stroke or cut-off), while at the same time the other passage 17 communicates with the chest beyond the other end piston 13 irrespective of the valve stroke, as seen by comparing Figs. 1 and 3.

30 Other steam passages 18 communicate at one end with the ends of the cylinder 2 and with the chest 7 at such points equal distances from the line 12 as to communicate with the spaces in the chest 7 just beyond the central pistons 14 when the valve is in its central position, as shown in Fig. 2.

35 When the piston valve is working on a long stroke or cut-off and is at the head end of its

stroke, the adjacent head end passage 18 communicates with the channel 15, while the other passage 18 still communicates with the chest between the lower pistons 13 and 14, as shown in Fig. 2. When, however, the valve is operating on a short stroke or cut-off said head end passage 18 is blocked off by the upper valve piston 14, as shown in Fig. 3.

Ports 19 connect the passages 18 and the chest 7 intermediate the ends of said passages and equal distances from said line 12. Said ports 19, when the valve is in a central position, then open to the chest between the corresponding pistons 13 and 14, as shown in Fig. 2, and the same is true when the piston valve is at either end of its stroke when operating on a short cut-off, as shown in Fig. 3. When, however, this valve is at the head end of its stroke on a long cut-off, the corresponding or adjacent port 19 is still open to the chest between the adjacent valve pistons, but the other port 19 is closed by the other end piston 14, as shown in Fig. 1. An exhaust pipe 20 leads from the cylinder 2 centrally of its ends or so as to be uncovered when the piston 4 is at either end of its stroke.

In operation, when it is desired to operate the engine simple, as when starting a load, the valve 9 is set for a long stroke by suitable manipulation of the linkage 11. The cranks 6 are set relative to the valve linkage so that when the valve is at the head end of its stroke, for instance, the piston 4 is at the head end of its cylinder, while the piston 3 is at the opposite end. Steam admitted to the chest 7 from pipe 8 then passes directly through the valve 9 to the ports 16 and into the channel 15, entering the head end passage 18, which then communicates with said chest, and then flows into the head end of cylinder 2 on top of the piston 4, as shown in Fig. 1, the other passage 18 being then idle.

At the same time steam is entering cylinder 1 at its opposite end through the corresponding passage 17, which is open to the chest beyond the valve. Said head end passage 18, however, also communicates with the head end of cylinder 1 through the adjacent port 19, the chest 7 between adjacent pistons 13 and 14, and the adjacent passage 17. The steam pressure in cylinder 1 is therefore balanced and the piston 3 then does little work. Steam taken into said cylinder at its head end, however, is forced into the cylinder 2 in a measured amount as the piston 3 moves toward the head end of the cylinder until the passage 17 is cut off by the adjacent valve piston 14. When the piston 4 reaches the end of its stroke the steam exhausts through the pipe 20 and fresh steam is then admitted to the opposite end of cylinder 2 in the same manner as above described, for the return stroke. The cylinder 2 is then operating on high pressure steam, as will be evident, and, due to the large size of the piston 4, exerts great starting torque on the crankshaft. When the need of this extra torque has passed, the valve linkage 11 is manipulated to set the piston valve on a short stroke. With the valve then at the head end of the chest, steam enters the lower end of cylinder 1 as before and passes out from above the piston 3 through the head end passage 17, which then communicates with the chest 7 between the adjacent valve pistons 13 and 14. The head end port 19, however, is also in communication with the chest between said pistons so that the previously expanded steam flows directly from cylinder 1 above the piston 3 into cylinder 2, so that

the latter then operates compound. When the cylinder pistons and valve reach the opposite ends of their stroke the spent steam in cylinder 2 passes out through pipe 20, and the entering flow of steam to said cylinder is of course reversed.

The engine may be operated partially simple by the use of a medium valve stroke; and the same engine operation and functioning may of course be obtained when the cylinders are disposed in tandem relation.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A steam engine comprising a counterflow cylinder and a uniflow cylinder having an exhaust port, a steam chest connected to a source of steam, steam passage means between the cylinders and chest and including the latter, and a valve adjustable as to length of stroke, movable in the chest and cooperating with the passage means to feed steam from the chest to one end of the counterflow cylinder and from the opposite end of the latter to the uniflow cylinder; or to feed steam from the chest to both cylinders simultaneously and depending on the length of stroke of the valve.

2. A steam engine including high and low pressure cylinders having pistons arranged for reciprocation in opposite directions, a steam chest connected to a source of steam, a valve manually adjustable as to length of stroke mounted for reciprocation in the chest, and means forming steam passages between the ends of the cylinders and the chest and communicating with the latter in such relation to the valve that said valve, when operating on one stroke length will cause steam to feed from the chest to one end of the high pressure cylinder and from the other end of the latter to the corresponding end of the low pressure cylinder; and so that said valve, when operating on another stroke length, will cause steam to feed direct from the chest to both cylinders at opposite ends thereof simultaneously, as well as to the same end of the low pressure cylinder from the other end of the high pressure cylinder.

3. A steam engine comprising a counterflow cylinder and a uniflow cylinder, a piston mounted in each cylinder said piston being operable to move alternately in relatively opposite directions, respectively, each of said cylinders being provided with an intake port at each end thereof and the uniflow cylinder being provided with an exhaust port substantially mid way of its length, a steam chest, means for connecting the steam chest to a source of steam supply, a slide valve operable within the steam chest, said valve, when in one position, opening communication from the steam chest to both ports in the counterflow cylinder and to one port in the uniflow cylinder, simultaneously, and said valve, when in another position, opening communication from the steam chest to the port in one end of the counterflow cylinder and from the port in the opposite end of said

counterflow cylinder to the port in the corresponding end of the uniflow cylinder.
